UNITED STATES PATENT OFFICE.

JAY CLARENCE RYERSON, OF WICHITA, KANSAS.

DESIGN FOR A POCKET-BOOK.

SPECIFICATION forming part of Design No. 37,394, dated April 11, 1905.

Application filed February 7, 1905. Serial No. 244,664. Term of patent 7 years.

To all whom it may concern:

Be it known that I, JAY CLARENCE RYERSON, a citizen of the United States, residing at Wichita, Sedgwick county, State of Kansas, 5 have invented a new, original, and ornamental Design for Pocket-Books, reference being had to the accompanying drawing, which illustrates the design by a view in perspective.

What I claim is—
The ornamental design for a pocket-book as shown.

JAY CLARENCE RYERSON.
